US0D1104405S

(12) **United States Design Patent** (10) **Patent No.:** **US D1,104,405 S**
(45) **Date of Patent:** ** *Dec. 9, 2025

(54) **CONFECTION**

(71) Applicant: **FERRARA CANDY COMPANY**,
Chicago, IL (US)

(72) Inventor: **Sean Oomens**, Huntley, IL (US)

(73) Assignee: **FERRARA CANDY COMPANY**,
Chicago, IL (US)

(*) Notice: This patent is subject to a terminal disclaimer.

(**) Term: **15 Years**

(21) Appl. No.: **29/963,451**

(22) Filed: **Sep. 17, 2024**

Related U.S. Application Data

(63) Continuation of application No. 29/897,082, filed on Jul. 11, 2023, now Pat. No. Des. 1,048,649, which is a continuation of application No. 29/838,966, filed on May 17, 2022, now Pat. No. Des. 994,266, which is a continuation of application No. 29/744,833, filed on Jul. 31, 2020, now Pat. No. Des. 951,586.
